Primary Examiner — Rebekah A Caruso(74) *Attorney, Agent, or Firm* — Bryan L. Baysinger; E. Eric Mills; Maynard Nexsen PC(57) **CLAIM**

The ornamental design for a point of sale device stand, as shown and described.

DESCRIPTION

FIG. 1 is a back perspective view of a point of sale device stand, showing my new design;

FIG. 2 is a front perspective view thereof;

FIG. 3 is a front view thereof;

FIG. 4 is a back view thereof;

FIG. 5 is a top view thereof;

FIG. 6 is a bottom view thereof;

FIG. 7 is a left side view thereof; and,

FIG. 8 is a right side view thereof.

The broken lines in FIGS. 1-8 depict environment that forms no part of the claimed design.

1 Claim, 7 Drawing Sheets(56)
